PERSPECTIVE DRAFTING DEVICE

Konstantin F. Harchikov, 450 Vermont St.,
Brooklyn 7, N.Y.

Filed Sept. 22, 1958, Ser. No. 762,373

3 Claims. (Cl. 33—77)

The present invention relates to a perspective drafting device. Its object is the provision of a device for drawing views in perspective with the vanishing points in any position, the most important application of the device being in cases where the vanishing points do not fall on the drawing table.

The particular application of the device is the drawing of a perspective simultaneously with that of the construction, on enlargement from a previous construction, or a perspective layout without a plan, elevation or section. This is applicable to different types of buildings, engineering constructions, numerous objects, details, etc.

In the accompanying drawings:

Figure 1 is a main elevation of the device of the present invention.

Figures 2 and 3 are side elevations of the device of the invention.

Figures 4 and 5 are longitudinal sectional views of the device of the invention, the sections being along the lines 4—4 and 5—5 of Fig. 1 looking in the direction of the arrows of said lines.

Figures 6, 7, 8, 9, 10, 11 and 12 are transverse sectional views of the device of the invention, the sections being taken along the lines 6—6, 7—7, 8—8, 9—9, 10—10, 11—11 and 12—12, respectively of Fig. 1, looking in the direction of the arrows of said lines.

Figures 13, 14 and 15 illustrate the use of the invention for operation above the line of horizon.

Figures 16, 17, and 18 illustrate the use of the invention for operation below line of horizon.

The perspective drawing device of the present invention includes two two-layered straight edges 1 and 6, similar in arrangement and alike externally (Figs. 1, 7 and 8), having upper members 2 and 6 fastened by screws 4. The straight edge 6 has a slot 7, which is used for guiding a pencil. The slot 7 is particularly useful for drawing lines with the straight edge 6 when the device is used for operations below the line of horizon. The straight edges 1 and 6 have channels or grooves (Figs. 7 and 8) which face each other and which serve to direct pins 5 moving along the channels in a lengthwise direction (Figs. 4, 9 and 10).

The perspective drafting device is provided with a mechanism connecting the two sets of straight edges and consisting of two identical adjusting bars 9 having holes 10 located in the center and along their entire length (Figs. 1 and 5). The ends of the adjusting bars 9 are of an oval shape and carry the pins 5, which slide in the channels of both straight edges (Figures 9 and 10).

A special rivet 3 can be inserted into any two superposed holes 10 of the adjusting bars 9, and serves to effect the operation of the perspective drafting device (Figures 1, 3 and 5).

The operation of the device is as follows:

Edge 1 of the perspective drafting device is placed on the line of horizon H—H of the drawing to be made, as indicated by full lines in Figs. 13 to 15. The other edge 6 is attached by tape 11 to the underlying sheet of

2

drawing below the line H—H. The device can be operated by inserting the special rivet 3 into any two superposed holes 10 of the adjusting bars 9.

The location of special rivet 3 in the center holes 10 (Fig. 13) provides a shifting of the straight edge 1 horizontally in an upward direction, and with a triangle vertical lines C—C are obtained.

The location of special rivet 3 in any of the holes 1 to 85 on the right hand side (Fig. 14) provides a shifting of the straight edge 1 upwardly from the line of horizon H—H at a variable angle. This provides lines C—C for a right hand vanishing point.

The location of special rivet 3 in any of the holes 1 to 85 on the left hand side (Fig. 15) provides a shifting of the straight edge 1 upwardly from the line of horizon H—H at a variable angle. This provides lines C—C for a left hand vanishing point.

For perspectives below the line of horizon H—H, the slot 7 of the straight edge 6 is placed on the line of horizon H—H while the straight edge 1 is taped by the tape 11 above the line of horizon H—H (Figs. 16 to 18).

The location of special rivet 3 in the center holes 10 (Fig. 16) provides a shifting of the straight edge 6 in a downward direction, and with a triangle vertical lines C—C are obtained.

The location of special rivet 3 in any of the holes 1 to 85 on the left hand side (Fig. 17) provides a shifting of the straight edge 6 and slot 7 downwardly from the line of horizon H—H at a variable angle. This provides lines C—C for a left hand vanishing point.

The location of special rivet 3 in any of the holes 1 to 85 on the right hand side (Fig. 18) provides a shifting of the straight edge 6 and slot 7 downwardly from the line of horizon H—H at a variable angle. This provides lines C—C for a right hand vanishing point.

I claim:

1. A perspective drafting device, comprising first and second straight edges each straight edge having a longitudinally extending groove, first and second elongated adjusting bars crossing each other and located in different planes, said first bar having a pin on one end slidably located in the longitudinal groove of said first straight edge close to one end of said first straight edge, a pin on the other end of said first bar slidably located in the longitudinal groove of said second straight edge close to an opposite end of said second straight edge, said second bar having a pin on one end slidably located in the longitudinal groove, first and second elongated adjusting bars crossing each other and located in different planes, said first bar having a pin on one end slidably located in the longitudinal groove of said first straight edge close to an opposite end of said first straight edge, each of said bars having a longitudinal row of holes, the rows of holes of the two bars being uniformly disposed and being adapted to be brought into alinement, and a rivet removably fitting into any two aligned holes of said rows of holes.

2. A perspective drafting device, comprising first and second straight edges, each of said straight edges having upper and lower members and screws interconnecting said members, the two straight edges having opposed longitudinally grooves, first and second elongated adjusting bars crossing each other located in different planes and having oval ends, a pin carried by one end of said first bar and slidably in the longitudinal groove of said first straight edge close to one end of said first straight edge, another pin carried by the opposite end of said first bar and slidably in the longitudinal groove of said second straight edge close to one end of said second straight edge, a third pin carried by one end of said second bar and slidably in the longitudinal groove of said first straight edge close to the opposite end of said first straight edge, a fourth pin carried by the opposite end

of said second bar and slidab in the longitudinal groove of said second straight edge close to the opposite end of said second straight edge, each of said bars having a longitudinal row of holes, the rows of holes of the two bars being uniformly disposed and being adapted to be brought into alinement, and a rivet removably fitting into any two alined holes of said rows of holes.

3. A perspective drafting device in accordance with claim 2, for use upon an underlying sheet of drawing, said device including a connecting member for remov- 10

4
ably fixing the position of any one of said straight edges upon said sheet.
